UNITED STATES PATENT OFFICE.

VENABLE J. GUTHRIE, OF CAMBRIA, VIRGINIA, ASSIGNOR OF ONE-EIGHTH TO JOHN C. GUTHRIE, OF PEARISBURG, VIRGINIA, AND ONE-EIGHTH TO WILLIAM C. GUTHRIE, ONE-EIGHTH TO HENRY D. JORDAN, AND ONE-EIGHTH TO FRANK GORDON, ALL OF DUBLIN, VIRGINIA.

AIR-COMPRESSOR.

1,226,328.

Specification of Letters Patent.

Patented May 15, 1917.

Application filed June 22, 1916. Serial No. 105,226.

To all whom it may concern:

Be it known that I, VENABLE J. GUTHRIE, a citizen of the United States, residing at Cambria, in the county of Montgomery and 5 State of Virginia, have invented a new and useful Air-Compressor, of which the following is a specification.

The present invention appertains to air and gas compressors and pumps, and aims to 10 provide a novel and improved machine for compressing air or gas.

The present invention has for its object the provision of an air or gas compressor embodying a novel assemblage of the component elements whereby the pump has a comparatively large capacity, has the capability of producing a high pressure with the least expenditure of power, is operable without the presence of sudden high compression 15 points to overcome, has its working parts well balanced and arranged to avoid undue vibration, and which will permit of a high speed of operation with the reciprocatory movement of the pistons or plungers. It is 20 also the object of the invention to provide a machine of this character in which the resistance against the operating means is practically steady, which is as simple as practical, which requires little floor space, being 25 compact and low, and which has its working parts inclosed.

A specific object of the invention is the provision in an air or gas compressor of novel means for effecting the compression 30 of the air or gas in a most efficient and practical manner, and another specific object of the invention is to provide novel means in connection with the reciprocatory pistons or plungers for admitting the air or gas.

40 A further object of the invention is the provision in the air or gas compressor of novel means for facilitating the lubrication of the working parts.

With the foregoing and other objects in 45 view which will appear as the description proceeds, the invention resides in the combination and arrangement of parts and in the details of construction hereinafter described, and claimed, it being understood 50 that changes in the precise embodiment of the invention herein disclosed can be made within the scope of what is claimed without departing from the spirit of the invention.

The invention is illustrated in the accompanying drawings, wherein:—

55

Figure 1 is a median vertical section of the compressor, taken on the line 1—1 of Fig. 2, portions being shown in elevation.

Fig. 2 is a vertical section taken on the line 2—2 of Fig. 1, portions being shown in 60 elevation.

Fig. 3 is an enlarged sectional detail of one of the balanced valves of the pistons.

Fig. 4 is a sectional detail of an unbalanced valve.

65

In carrying out the invention, there is provided a suitable base 1 upon which is mounted a casing 2 providing the compression chamber. The casing 2 is preferably spherical for purpose of strength and appearance, 70 and the lower open end of the casing 2 is flanged and bolted or otherwise secured upon the edge of the base 1, there being a suitable gasket or packing between the casing 2 and base to prevent leakage. The 75 base 1 and casing 2 are each cast of suitable metal and the base is provided with opposite bearings or bearing brackets 3 in which the terminal portions of a crank shaft 4 are journaled, said crank shaft being seated between the adjacent edges of the base 1 and casing 2. A fly wheel 5 is secured to one end of the crank shaft and a pulley wheel 6 to the other whereby the crank shaft can be belted to an engine or prime mover. It 80 is to be understood, however, that the crank shaft can be driven from any available source of power, which can be connected either directly or indirectly with the crank shaft. The base 1 is provided with a bearing or pedestal 7 in which the intermediate portion of the crank shaft is journaled, and suitable packing means 8 are employed for preventing leakage around the crank shaft where it extends from the interior to the exterior of the casing. The base 1 is provided 85 with a pair of basins or sumps 9 for containing oil or other lubricant, and the two oppositely extending cranks of the shaft 4 are movable within said sumps 9 whereby 90 to splash the oil for applying the lubricant to the adjacent working parts. The sumps 9 have lower apertures or openings 10 for draw off plugs, which can be removed for drawing off the oil, especially the surplus 95 oil, from the sumps 9, whereby the oil drawn

90

95

100

105

off can be filtered and again used. The casing 2 is provided at one side with a handhole 11, normally closed by a hand hole cover 12 which is sealed by means of a gasket or 5 other packing to prevent leakage. The casing 2 is provided at a suitable point with an air or gas outlet 13 to which a pipe or other conduit can be connected for conducting the compressed air to the desired point.

10 In the construction illustrated, a pair of vertical twin cylinders 14 are used, although any suitable number of cylinders can be used, and the cylinders 14 are preferably cast *en bloc*. Said cylinders 14 are fitted

15 within the upper open end of the casing 2 and are equipped with a water jacket 15 provided between the upper and lower ends of the cylinders with an outstanding flange 15^a bolted or otherwise secured upon the 20 upper end of the casing 2. A suitable gasket or other packing is preferably disposed between the flange 15^a and the casing 2 to prevent leakage, and the water jacket 15 has the inlet and outlet openings or ports 25 16 and 16^a, respectively, whereby water or other cooling fluid can be circulated through the water jacket around the cylinders. The upper protruding ends of the cylinders are covered by a common head or plate 17.

30 Slidably mounted for vertical movement in the cylinders 14 are the tubular or sleeve-shaped pistons or plungers 18, which are preferably provided with packing rings adjacent their upper ends, and said pistons are provided adjacent their lower ends with diametrical wrist pins 19 having their intermediate portions offset downwardly whereby the axes of said intermediate portions lie in the planes of the lower ends of the respective 35 pistons. A pair of connecting rods 20 have their upper ends journaled upon the intermediate portions of the wrist pins 19, and have their lower ends journaled upon the cranks of the crank shaft 4. When the 40 crank shaft is rotated, the connecting rods will therefore impart reciprocatory movement to the pistons, the pistons reciprocating in opposite directions whereby the compressor will be double acting.

45 A displacement cone or tapered member 21 has its lower smaller or apical portion embracing and mounted upon each connecting rod 20 and secured thereto by means of a cotter pin 22 or other securing element, and the upper larger end of the cone is 50 open and arranged immediately adjacent to the lower end of the respective cylinder 18. The upper ends of the cones are cut at an obtuse angle, as seen in Fig. 2, whereby the 55 cones can swing with the crank shafts. When the connecting rod of each piston is 60 in vertical position, opposite openings are provided between the cone 21 and piston, and when the crank shaft is arranged at its 65 extreme angular position at either side, one

side portion of the cone abuts against or is immediately adjacent to the lower end of the piston and there is an opening between the opposite side portion of the cone and piston, as seen in Fig. 2. To permit the 70 upper larger ends of the cones to work adjacent the lower ends of the pistons, the wrist pins 19 are offset downwardly as above described.

75 The pistons 18 are provided at their upper ends with valves, which as illustrated in Figs. 1, 2 and 3 are of a special automatic balanced type. Threadedly or otherwise removably engaged with the upper end of each piston 18 is a ring or annulus 23 having an inner V-shaped edge providing a downwardly facing beveled valve seat 24 against which the upwardly facing beveled portion 25 of an upwardly seating puppet valve 26 is seatable. Each of the pistons 80 is provided with one of said valves, and each valve is provided with a depending sleeve 27 slidable upon a cylindrical head 28 which is preferably provided with packing rings bearing against the sleeve 27 to 85 prevent leakage. The head 28 is threadedly or otherwise engaged upon a post 29 having its lower end secured in any suitable manner to a diametrical cross bar 30 with which the piston 18 is provided between its ends. 90 A spiral spring 31 is disposed within the sleeve 27 and is confined between the head 28 and valve 26, to raise said valve against its seat. The valve 26 is provided with a central frusto-conical opening 32 providing 95 an upwardly facing valve seat carried by the valve 26, the opening 32 communicating with the upper end of the chamber or bore of sleeve 27, and a puppet valve 33 is seatable downwardly within the opening 32 100 and has a depending stem 34 slidable through a spider 35 with which the valve 26 is provided within the upper end of the sleeve 27. A coiled wire expansion spring 105 36 surrounds the stem 34 and is confined between the spider 35 and a nut or equivalent element 37 upon the lower end of the stem 34, whereby to normally close the valve 33 with sufficient spring tension. The 110 valve 26 is provided with diverging ducts or passages 38 extending from the chamber of the sleeve 27 to the upwardly facing beveled portion 25 of the valve which seats against the valve seat 24, whereby said passages or bores 38 are normally closed by the 115 valve seat.

120 Threadedly or otherwise engaged to the head 17 of the cylinders are annular members 39 providing air inlet ports in the common head 17 of the cylinders, and said members 39 have arches 39^a bridging or spanning the same and provided with upstanding sleeves 40. The lower edges of the members 39 provide seats for disk or puppet valves 41 which are seatable upwardly 125 130

against said members 39, and said valves 41 have upstanding stems 42 slidable through the lower closed ends of the sleeves 40 and projecting upwardly out of said sleeves.

5 The valves 41 are the air inlet valves which permit air to flow into but prevent the air from flowing backwardly out of the cylinders. A nut 43 is threaded upon the stem 42 of each valve 41 and fits slidably within the upper end of the respective sleeve 41 and a lock nut 44 is threaded upon the upper end of the stem 42 and provides a seat for the nut 43. A coiled wire expansion spring 45 is disposed within each sleeve 40 and is confined between the lower end of said sleeve and the nut 43, whereby to raise the stem 42 and the valve 41. The tension of the spring 45 is regulated by adjusting the nut 43.

10 A drop feed oil or lubricant cup 46 is disposed above each cylinder and is provided with a discharge tube or spout 47 engaged through the respective arch 39^a to overhang the valve 41, whereby the oil drips from the tube 47 onto the valve 41, in order that when

15 said valve is unseated by the air suction, the inflowing air will spray the oil to the walls of the cylinder, the valve 26 and other working parts whereby to lubricate them. The surplus oil flows downwardly and drips

20 from the cylinders into the oil sumps 9, the oil also flowing downwardly along the pistons to lubricate the connecting rods. Thus, by the provision of the means for delivering oil onto the air intake valves 41, in connection with the sumps 9 in which the cranks of the crank shaft 4 dip, the various working parts of the compressor are lubricated in a

25 most effective manner.

In operation, supposing the crank shaft 40 to be rotated, the pistons 18 will reciprocate in opposite directions. When one piston is moved downwardly so as to be projected into the compression chamber, the corresponding displacement cone 21 is moved ahead of said

45 piston, and by its "wedging" action will displace the air, thus bringing it under pressure with the least resistance and friction, and without a jar or shock. When the pistons are reciprocated at a high velocity, the

50 cones 21 are effective for assisting in the compression of air. Thus, when each cone is moved at a high speed with the connecting rod into the compression chamber, the movement of the cone into said chamber dis- 55 places the air, that is to say, the movement of the cone with its apex foremost causes the oblique sides of the cone to impinge against the air and deflect it radially away from the cone, due to the motion of the cone,

60 thereby compressing the air in the casing 2. During the stroke of the downwardly moving piston, the valve 6 thereof remains seated, whereby there is a tendency to produce a vacuum in the respective cylinder above the 65 piston, and as a result, air will be drawn

into said cylinder through the air inlet member 39, the valve 41 being unseated. While one piston is moving downwardly, the other is moving in the opposite direction, and as a result the air within the cylinder of the upwardly moving piston is compressed, the valve 41 being seated, and the valve 26 being opened whereby the compressed air is delivered into the upwardly moving piston 18 and displacement cone 21, the air flowing from between said piston and cone into the compression chamber, whereby to compensate for the air discharged by displacement through the outlet 13. Thus, as the pistons reciprocate in opposite directions, there is a practically continuous displacement of air in the casing 2, thereby providing a steady continuous flow of air, which is almost entirely free of pulsations, one piston and its displacement cone always being operative for displacing the air in the compression chamber while air is supplied to the compression chamber by way of the other piston.

70 By the provision of the balanced valves 26 of the pistons 18, the uniform pressure of the air in the casing 2 is enhanced. The balanced valve is so designed that the pressure area of the upwardly facing beveled portion 25 is the same as the pressure area of the fixed head 28 in the piston, whereby 75 the pressure area of the upper face of the valve 26 which is exposed through the opening of the ring 23 is the same as the pressure area of the lower exposed surface of the valve 26 and its sleeve 27, so that the valve 26 is balanced with respect to the pressure upon the upper and lower surfaces thereof. When the piston moves upwardly, the valve 26 is seated during the initial upward movement of the piston, whereby the portion 25 is cut off from the pressure above the piston, and the passages 38 are closed by the valve seat 24, so that the valve 26 will 80 unseat at practically a balance of the pressures in the upper end of the cylinder and the compression chamber. When the valve 26 is unseated by the slightly greater pressure in the cylinder above the piston, the air pressure above the piston now acts upon the entire upper surface of the valve 26, 85 and to prevent the unbalancing of the valve when it is unseated, the passages 38 are provided. Therefore, when the valve 26 is unseated, air will flow through the passages or bores 38 into the chamber of sleeves 27 and the air within said chamber being brought under pressure will act upwardly 90 against the valve 26 thus balancing the valve, since the upward pressure thereagainst will be practically the same as the 95 downward pressure imposed upon the valve, the secondary or supplemental valve 33 remaining seated under the influence of its spring 36. The valve 26 being balanced will 100 operate easily and quickly, and when the 105

piston has reached the end of its upward stroke and starts downwardly, the pressure below the secondary valve 33 as well as the creation of a partial vacuum above it quickly opens said secondary valve and the air is therefore sucked from the chamber of sleeve 27 upwardly through the opening 32, and the valve 33 will immediately close, thereby again balancing the valve 26 as it seats during the initial downward movement of the piston, it being noted that the passages 38 being closed when the valve 26 is seated renders the secondary valve 33 useful in permitting the pressure to escape from the sleeve 27. The spring 31 unassisted serves to seat the valve 26, and is of such tension as to accomplish the seating of said valve quickly and with certainty.

A simple unbalanced valve for use with each piston instead of the balance valve, is shown in Fig. 4, and is designated 26'. This valve 26' has a depending sleeve 27' slidable upon the post 29' attachable to the cross bar of the piston, and a coiled expansion spring 31' is disposed within the sleeve 27' between the post 29' and the valve 26' for seating said valve. The sleeve 27' has passages or bores 38' extending to the chamber thereof for the ingress and egress of air as the valve 26' reciprocates relative to the post 29'.

The construction and arrangement of parts are such that the desired objects are carried out in a satisfactory manner. Friction and resistance are reduced to a minimum, and the construction is apparently simple and inexpensive. The compressor can be operated at a minimum expense and will require but little attention. The consumption of oil is small, and the various parts in being nevertheless thoroughly lubricated, will render the machine long lived.

As illustrated in the drawings, the balanced valves and their seats are provided with beveled contacting surfaces, but if desired, by a very slight change in design, as will be apparent to those skilled in the art, the contacting surfaces of the valves and their seats can be flat.

Having thus described the invention, what is claimed as new is:

1. A compressor embodying a compression chamber, a cylinder communicating therewith at one end and having an inlet at its other end, a valve for said inlet, a tubular piston slidable in said cylinder, a valve carried by the piston seatable toward the inlet, a crank shaft, a connecting rod connecting the crank shaft and piston, and a displacement cone upon the connecting rod having its larger end arranged adjacent to the piston, the chamber having an outlet.

2. A compressor embodying a compression chamber, a cylinder having one end communicating with said chamber and hav-

ing an inlet at its other end, a valve for said inlet to prevent the outward flow of air therethrough, a tubular piston slidable in said cylinder having a valve seat at that end nearest said inlet and having a wrist pin at its other end offset away from said inlet, a crank shaft having a crank working within said chamber, a connecting rod connecting said crank and wrist pin, and a displacement cone having its apical portion secured upon the connecting rod, the larger end of the cone being open and cut at an obtuse angle to work adjacent the end of the piston, and said chamber having an outlet.

3. A compressor embodying a compression chamber having an outlet, a pair of cylinders having certain ends communicating with said chamber and having inlets at their other ends, valves for said inlets to prevent the flow of air outwardly therethrough, tubular pistons slidable in the cylinders, valves carried by the pistons seatable toward said inlets, means for reciprocating the pistons in opposite directions, and displacement cones associated and movable with the pistons and working within said chamber, the larger ends of the cones being arranged adjacent to the pistons and having portions spaced therefrom to provide openings.

4. A compressor having a compression chamber having an outlet, a cylinder having one end communicating with said chamber and having an air inlet at its other end, a valve for closing said inlet, a piston slidable within the cylinder, the piston having a valve seat facing away from the inlet, a spring pressed valve seatable against said seat and having a chamber and air conducting means extending from the chamber to that portion which rests against said seat, the second mentioned valve having an opening communicating with said chamber and with that end of the cylinder having the inlet, and a spring seated valve carried by the second mentioned valve and seatable away from the first mentioned valve to close said opening.

5. A compressor embodying a compression chamber having an outlet, a cylinder having one end communicating with said chamber and having an air inlet at its other end, a valve for closing said inlet, a piston slidable within the cylinder and having a beveled valve seat facing away from the inlet, a spring pressed valve having a beveled portion seatable against said seat and having a chamber, the second mentioned valve having air conducting means extending from said chamber to said beveled portion and normally covered by said seat when the second mentioned valve is seated, the second mentioned valve having an opening communicating with said chamber, a third valve seatable to close said opening, the third mentioned valve being seatable away from the

first mentioned valve, and spring means within said chamber for seating the third mentioned valve.

6. A compressor embodying a compression chamber having an outlet, a cylinder having one end communicating with said chamber and having an air inlet at its other end, a valve for closing said inlet, a tubular piston slidable within the cylinder, means for reciprocating said piston, the piston having a valve seat facing away from the inlet, a post within the piston carried thereby, a head carried by said post, a valve seatable against said seat and having a sleeve projecting away from the inlet and slidable upon said head, an expansion spring confined between said head and second mentioned valve, the second mentioned valve having air conducting means extending from the chamber of said sleeve to the portion of said valve which rests against said seat, said valve having an opening communicating with the chamber of said sleeve and with that end of the cylinder having the inlet, and a spring seated valve carried by the second mentioned valve and seatable away from the first mentioned valve to close said opening.
7. A compressor embodying a compression chamber having an outlet, a cylinder having one end communicating with said chamber and having an air inlet at its other

end, a valve for closing said inlet, a tubular piston slidable within the cylinder, means for reciprocating said piston, the piston having a beveled valve seat facing away from the inlet, a post within the piston and carried thereby, said post projecting toward the inlet, a head carried by said post, a second valve having a beveled portion seatable against said seat and having a sleeve projecting away from the inlet and slidable upon said head, the second mentioned valve having air conducting means extending from the chamber of said sleeve to said beveled portion and normally covered by said seat when the second mentioned valve is seated, the second valve having an opening communicating with the chamber of said sleeve, and a spider within said sleeve, an expansion spring confined between said head and second valve, a third valve seatable to close said opening of the second valve and having a stem slidable through said spider, and a spring between said spider and stem for seating the third valve.

In testimony that I claim the foregoing as my own, I have hereto affixed my signature in the presence of two witnesses.

VENABLE J. GUTHRIE.
